UNITED STATES PATENT OFFICE.

RAY G. COATES, OF PASADENA, CALIFORNIA, ASSIGNOR TO VALLEY MOULD AND IRON CORPORATION, OF SHARPSVILLE, PENNSYLVANIA, A CORPORATION OF NEW YORK.

RUNNER TILE.

Original application filed April 21, 1921, Serial No. 463,160. Divided and this application filed July 13, 1923. Serial No. 651,242.

To all whom it may concern:

Be it known that I, RAY G. COATES, a citizen of the United States, residing in Pasadena, in the county of Los Angeles, State of California, have invented certain new and useful Improvements in Runner Tile, of which the following is a specification.

This invention relates broadly to metallurgy and more especially to a runner tile adapted more particularly to horizontal molds for casting ingots.

Heretofore in the art it has been customary to use various type of runner tiles which in substantially all cases were unitary structures with openings running therethrough. Unitary structure tiles usually represent a larger integral mass of tile which is liable to crack or break when in use and also which does not lend itself easily to heating up due to the relatively large mass and due to the fact that the interior cavities are usually heated at a different rate from the exterior of the tile.

The present invention overcomes the difficulties of the known art by providing a runner tile formed in sections in such manner that each section carries a part of the runner tile opening and that the sections themselves, relatively speaking, are flat tile-like members. Furthermore, the opening through the tile is preferably formed in such manner that when the sections of the tile are assembled the completed opening is oval in cross section so that the gate may be easily broken after the ingot is frozen. Preferably also the tile is wedge-shaped and is arranged to set in the mold body in such manner as to lift out when the ingot is stripped from the mold. This facilitates re-use of the runner tile, because the sections of the tile fall away from the gate without the necessity of breaking the tile to remove it from the ingot.

In view of the foregoing it may be stated that the principal object of the invention is to provide a runner tile for metallurgical use which tile is formed in two sections in such manner as to easily be stripped from the metal forming the root in the runner tile when the metal solidifies.

A still further object of the present invention is a runner tile provided with an oval runner conduit whereby the necessary

cross sectional area of the runner conduit 55 may be obtained in a tile which is relatively thin and narrow.

A still further and more specific object of the present invention is a runner tile of the character specified wherein sand grooves 60 are provided on the sides of the runner tile to form a sand belt around the runner tile to stop leakage and at the same time prevent formation of fins around the tile from metal in the matrix of the mold. 65

Other and further objects of the present invention will in part be obvious and will in part be pointed out hereinafter in the specification following by reference to the accompanying drawings, wherein like parts 70 are represented by like characters throughout the several figures thereof.

Realizing that the present invention may be embodied in constructions other than those herein specifically disclosed, it is desired that the present disclosure shall be considered as illustrative and not in the limiting sense. 75

Figure 1 is a view of a mold with the parts thereof separated to show one form 80 of construction in which the runner tile comprising the present invention may be utilized.

Figure 2 is a front elevational view of 85 the runner tile.

Figure 3 is a side elevation of the runner tile.

Figure 4 is a back view of the runner tile.

Figures 5 and 6 illustrate the runner tile 90 separated in order to show the formation of the runner conduit.

Figure 7 is a top view of the runner tile.

Figure 8 is a base view of the runner tile. 95

Figure 9 is a perspective view of a modified form of the invention.

Referring now to the drawings, the mold will only be referred to in a general way because it is specifically described and claimed in my copending application Serial 100 Number 463,160, filed April 21, 1921, of which the present application is a division. Referring therefore to the mold in a general way it is preferably formed of sections, the lower one comprising a stool 1 105 provided with a head closing member 2. The body of the mold comprises an inverted trough member 4 and the fountain 5 of the

mold is adapted to set upon and cooperate with the end of the body portion 4 and with the head closing member 2. Preferably the head closing member 2 in the present embodiment is provided with a wedge-shaped opening into which the runner tile structure is adapted to fit.

The runner tile is formed of sections 6 and 7 which may be easily and cheaply formed by dies in suitable presses. Shallow grooves 8 and 9 are formed in the contiguous faces of the sections so that the desired runner channel 10 is formed when the parts are assembled. The plane of separation of the parts of the tile preferably is along the vertical longitudinal plane of the ingot, which passes through the major cross-sectional axis of the runner channel. It will be noted that when the sections are assembled the cross-sectional boundary of the runner tile channel is oval in shape with sharp angular corners adjacent the plane of separation of the two parts. This gives greater clearance and allows each half of the tile to be readily separated from the solidified runner or gate which is left in the tile after casting. This construction permits stripping the tile without breaking so that it may be used over again until it becomes unfit for use.

Preferably one section is provided with a groove 11 and the other section is provided with a tongue 12 which is adapted to fit into the groove and to position the parts in such manner as to properly form the runner opening 10. The sides of each section are recessed as at 14 to provide sand grooves which meet beneath the runner tile. Preferably a smaller sand groove 15 is provided in the back of the tile as well as at the side. The front of the tile is cut away as at 16 to provide a vent opening for the mold gases. The tile illustrated in Figures 1 to 8 illustrates a tile tapering downward, whereas the tile illustrated in Figure 9 shows a modified form of the tile tapering backward.

In setting the tile, a thick clay wash may be brushed on the tile in a narrow strip on portions where the tile contacts with the walls of the recess, then after the tile has been set a loose fine dry "refractory" sand, may be run into the sand grooves and between the tile and its respective recesses in which it sets. This fine material will readily penetrate around the tile while the clay wash will prevent leakage of the sand into the mold.

It is evident that these sand groove constructions increase the clearance space between the tile and the tile cavity so that the tile is quickly relieved of pressure when the ingot is stripped, and facilitates setting the tile after the mold has been set up because considerable clearance permits of

easily manipulating the parts of the original setup.

Having thus described my invention, what I claim is:

1. As an article of manufacture, a runner tile for horizontal molds and the like comprising a plurality of parts provided with sand grooves in the side walls thereof. 70

2. As an article of manufacture, a wedge runner tile for horizontal molds and the like comprising a plurality of parts provided with sand grooves in the side walls thereof. 75

3. As an article of manufacture, a runner tile for horizontal molds and the like comprising a plurality of parts provided with an L-shaped conduit opening and sand grooves in the side walls thereof. 80

4. As an article of manufacture, a wedge runner tile for horizontal molds and the like comprising a plurality of parts provided with an L-shaped conduit opening and sand grooves in the side walls thereof, said conduit being oval in cross-section. 85

5. As an article of manufacture, a runner tile for casting horizontal ingots and the like comprising a plurality of sections, provided with sand grooves on the sides of the runner tile, which sand grooves meet at the bottom of the runner tile. 90

6. As an article of manufacture, a reusable runner tile for casting horizontal ingots and the like comprising a plurality of sections, provided with sand grooves on the sides of the runner tile, which sand grooves meet at the bottom of the runner tile and an oval shaped runner conduit with half the conduit in one section and the other half in the other section. 95

7. As an article of manufacture, a runner tile for casting horizontal ingots and the like comprising two sections, said sections being provided with sand grooves on the outer sides of the runner tile, which sand grooves meet at the bottom of the runner tile. 105

8. As an article of manufacture, a reusable runner tile for casting horizontal ingots and the like comprising two sections, said sections being provided with sand grooves on the outer sides of the tile, which sand grooves meet at the bottom of the runner tile and an oval shaped runner conduit with half of the conduit in one section and the other half in the other section. 110

9. As an article of manufacture, a half-section of a runner tile for horizontal molds and the like provided with half of an oval shaped runner conduit, and sand grooves on the side of said half-section opposite the runner conduit. 120

10. As an article of manufacture, a runner tile for horizontal molds and the like provided with an oval shaped runner conduit and a gas outlet channel on the front face of the said runner. 125

11. As an article of manufacture, a runner tile for horizontal molds and the like comprising a plurality of sections each being provided with a portion of an oval shaped 5 runner conduit and a gas outlet channel on the front face of the said runner, and sand grooves on the outside of said sections.

12. As an article of manufacture, a section 10 of a runner tile for horizontal molds and the like having a cavity extending along one side of the section from the upper end thereof to a point adjacent the lower end of the section and sand grooves on the other side of said section.

15 13. As an article of manufacture, a section of a runner tile for horizontal molds and the like having a cavity extending along one side of the section adapted to cooperate with a similar section to form a conduit, 20 oval shaped throughout its length, and sand grooves in the other side of said section.

14. As an article of manufacture, a half 25 section of a runner tile for horizontal molds and the like, provided with half of an oval shaped runner conduit, said portion of a conduit being vertically disposed and extending substantially between diagonal corners of one surface of the section.

15. As an article of manufacture, a run-

ner tile for horizontal molds and the like, 30 provided with sand grooves on the sides thereof extending substantially from the top to the bottom of said tile.

16. As an article of manufacture, a runner tile for horizontal molds and the like 35 provided with sand grooves on the sides thereof extending substantially from the top to the bottom of said tile, and having a substantially L-shaped conduit extending through said runner tile. 40

17. As an article of manufacture, a runner tile for horizontal molds and the like provided with a vertically disposed conduit, 45 said conduit being oval-shaped in cross-section substantially throughout its length. 45

18. As an article of manufacture, a runner tile for horizontal molds and the like comprising a plurality of sections, each being provided with a portion of a vertically disposed conduit, said conduit being substantially oval-shaped in cross section 50 throughout its length.

19. As an article of manufacture, a runner tile for horizontal molds and the like provided with sand grooves on the sides 55 thereof which extend from the top of the runner tile and meet at the bottom thereof.

RAY G. COATES.
